UNITED STATES PATENT OFFICE.

WILLIAM G. HARSHIN, OF NEWBURG, ASSIGNOR TO FERRY & NAPIER, OF NEW YORK, N. Y.

PRESS FOR HAT-BRIMS.

SPECIFICATION forming part of Letters Patent No. 406,214, dated July 2, 1889.

Application filed February 5, 1889. Serial No. 298,702. (No model.)

To all whom it may concern:

Be it known that I, WILLIAM G. HARSHIN, of Newburg, in the county of Orange and State of New York, have invented a new and useful Improvement in Presses for Hat-Brim, of which the following is a full, clear, and exact description.

This invention relates to presses for pressing and finishing the brims of felt and wool hats, in which a hinged platen is used and operates in connection with a metal bed having a suitable aperture through it to receive the body and crown of the inverted hat within it, and having a jacket on its under side arranged to come below the brim of the hat, and to which steam is admitted to heat the brim from what constitutes, when finished, its outer side, while or afterward the hinged platen is brought down, by a suitably-attached lever or otherwise, to bear upon the opposite or inner side of the brim.

The object of the invention is to apply in a simple and practicable manner to such a press means whereby the hinged platen may also be positively heated to subject the inside surface of the hat-brim to a proper heating and pressing action, as well as the opposite side of the brim, which rests upon the bed, whereby not only a much greater number of hats may be worked off in a given time, but a superior finish be given, especially to the inner surface of the brim of the hat. The special means by which this is accomplished are not made up exclusively of steam or other like heating-jackets applied both to the bed and follower of a hat-brim press; but the invention consists in a combination, with a suitably constructed and jacketed bed and a suitably constructed and jacketed hinged platen, of heating-medium-circulating pipes connected at their forward ends with the heating belt or jacket of the platen and arranged to turn in sockets in the rear in axial line with the hinge center of said platen, substantially as hereinafter described, and pointed out in the claim, and for a specific purpose or purposes, as will be herein set forth.

Reference is to be had to the accompanying drawings, forming a part of this specification,

in which similar letters of reference indicate corresponding parts in all the figures.

Figure 1 represents hat-brim press of the description hereinbefore specified with the platen down and having my improvement applied, certain portions being broken away and in section to illustrate interior construction. Fig. 2 is a horizontal section through the bed of the press; Fig. 3, a vertical transverse sectional view with the platen down and press closed, and showing a hat as under operation within the press; and Fig. 4, a side elevation of the press, partly in section, when open and with the platen raised or thrown back.

A is the bed of the press, having an aperture c of any desired size and shape adapted to receive the body and crown of a hat B down within it, and constructed with a jacket d beneath, into which steam or other heating fluid or gas is introduced and allowed to circulate, as by pipes e e, for the purpose of heating the outer surface of the brim b of the hat, which, when the inverted hat is inserted in the press, lies upon the bed over its jacket d.

C is the platen of the press in jointed connection intermediately of its length, as at f, with a hand-lever D, which has its fulcrum at g in lugs h h on the back end of the bed-plate. This construction and attachment makes the platen C a hinged or swinging one. Said lever D is provided with a side handle i for raising and lowering it with its attached platen, and, as in other hinged-platen presses, is further provided with a cam-shaped projection k in front for a second lever E, pivoted below at l to the bed, to bear down upon, by means of an attached roller m, for the purpose of giving an additional squeeze or pressure to the platen when down.

The platen C is constructed on its top or back with a hollow continuous belt or jacket n, arranged so that when the platen is down it comes opposite the jacketed portion d of the bed outside of the aperture c therein and over the inner surface of the brim of the inverted hat. This hollow belt or jacket d is also supplied with steam, heated fluid, or gas, so that when the platen is brought down on

the brim of the hat it directly applies the requisite heat to the inner surface of the brim as the jacketed bed does to the opposite surface thereof, thus subjecting both surfaces 5 of the brim to the necessary heat and pressure without delay. To thus introduce the steam or heating-fluid to the jacket *n* of the hinged platen without breaking or impairing the connections for introducing the same, and 10 to do this in a more durable and practicable manner than is ordinarily attainable by rubber or flexible tube connections, I connect the belt *n* of the platen on opposite sides of the press—say on a level with the joint-pin *f*, as 15 through hollow uprights *o o*—by elbowed pipes *b' c'*, with hollow projection *s s* at the back end of the bed in open communication with the jacket *d* of the bed, whereby one set of main pipes serve to supply both jackets *d* and 20 *n* with the requisite steam, heating-fluid, or gas, and the pipes *b' c'* are so arranged that the pipes *c'*, which are socketed to freely 25 turn within glands applied to the uprights *s s*, will, in all workings of the platen up and down, occupy a horizontal or line position

with the axis of the hinge of the platen or fulcrum-pin *g*.

Having thus described my invention, what I claim as new, and desire to secure by Letters Patent, is—

In a press for pressing and finishing the brims of felt and other like hats, the combination, with the bed *A*, having a hat-body-receiving aperture *c*, and steam or other heating jacket *d* on its under side outside of said aperture, of the hinged platen *C*, having a steam or other hollow heating-belt *n* on its top for operation in connection with the heating-jacket on the under side of the bed upon the brim of the hat, as described, and the 30 heating-medium-circulating pipes *b' c'*, connected at their forward ends with the belt *n* of the platen and supported by and adapted to turn in sockets in the rear in axial line with the hinge-pin of the platen, substantially 35 as specified.

WM. G. HARSIN.
